CLAIM

The design for a substrate for manufacturing cutting elements, as shown and described herein.

DESCRIPTION

FIG. 1 is a perspective view of a substrate showing my new design;

FIG. 2 is a top plan view of the substrate of FIG. 1;

FIG. 3 is a side elevation view of the substrate of FIG. 1; and,
FIG. 4 is a bottom plan view of the substrate of FIG. 1.

1 Claim, 4 Drawing Sheets
